J. P. SIMPSON.
SMOKELESS ORCHARD HEATER.
APPLICATION FILED MAR. 27, 1917.

Patented Jan. 15, 1918.

FIG. 2.

INVENTOR
JOSEPH PAXTON SIMPSON

or *Hazard E Miller*

UNITED STATES PATENT OFFICE.

JOSEPH PAXTON SIMPSON, OF POMONA, CALIFORNIA.

SMOKELESS ORCHARD-HEATER.

1,253,288.

Specification of Letters Patent. Patented Jan. 15, 1918.

Application filed March 27, 1917. Serial No. 157,662.

To all whom it may concern:

Be it known that I, JOSEPH PAXTON SIMPSON, a citizen of the United States, residing at Pomona, in the county of Los Angeles and State of California, have invented new and useful Improvements in Smokeless Orchard-Heaters, of which the following is a specification.

My invention relates to orchard heaters, 10 my object being to improve the details of construction with a view of producing more perfect combustion, and my invention consists in the novel features herein shown, described and claimed.

15 Figure 1 is a view in side elevation illustrating the heater assembled and ready for use.

Fig. 2 is a view in plan illustrating the heater shown in Fig. 1 and particularly 20 disclosing the design of the baffle wall within the fuel container.

Referring more particularly to the drawings, 10 indicates a liquid fuel container which is here shown as rectangular in shape 25 and formation and adapted to rest flat upon the ground. This container is provided with a cover 11 formed with openings 12 and 13 at its opposite ends. The opening 12 is fitted with a cylindrical sleeve 14 which 30 extends upwardly and is covered by a telescoping cap 15 positioned thereover. The sleeve is formed with a series of perforations adapted to adjustably register with similar perforations 16 formed through the 35 cylindrical side wall of the cap. An operating handle 17 is fixed to the top of the cap and provides adequate means for permitting the cap to be rotated upon the sleeve in a manner to regulate the draft within a 40 container 10. The handle 17 also permits the cap to be readily removed from the sleeve when it is desired to fill the container.

The opening 13, at the opposite end of the cover 11, is fitted with a vertically extending pipe 18. A flue drum 19 is secured at the upper end of this pipe and in communication therewith. This drum is of enlarged dimensions and is formed with a series of perforations 20 at its lower end 50 through which a draft will pass to unite with the gaseous fuel which passes upwardly through the pipe 18 and into the drum 19, thereby causing proper combustion thereof. A baffle plate 21 is positioned 55 within the drum 19 and spaced a distance from the opening through which the drum

communicates with the pipe 18. This plate prevents an excessive draft through the apparatus and also retards the gaseous fuel as it passes into the drum so that it will more 60 properly unite with the oxygen passing into the drum through the openings 20 and thereafter produce a more efficient combustion of the gas. It will be noted that the lower row of perforations 20 are positioned beneath 65 the horizontal plane of the baffle plate 21 and will cause combustion therebeneath in a manner to effectively eliminate the accumulation of carbon which would otherwise collect and in time render the apparatus inoperative. The main portion of the drum 19 extends upwardly a considerable distance 70 and carries away the gases produced by the combustion of the fuel. A series of stay rods 22, 23 and 24 are pivotally fixed to the 75 sides of the drum 19 and are adapted to extend within the ground around the bottom of the fuel reservoir in a manner to firmly support the drum.

In operation, fuel is placed within the reservoir 10 and allowed to encircle around a baffle wall 25 which is positioned at a point adjacent the vertical pipe 18 and the opening 13 through the top of the reservoir. This wall forms side passages 26 and 27 80 around which the gas and flame may circulate and which will permit the gas produced in the device to pass to the drum 19. When the apparatus is used, the cap 15 is removed and the liquid fuel within the reservoir is 85 ignited. The cap is then placed in position over the sleeve 14 and regulated so that there will be sufficient oxygen within the reservoir to produce proper generating combustion. Care is taken to see that but a 90 small draft will be established through the reservoir so that a slow burning flame will result within the container. This flame will heat the liquid fuel and cause it to be converted into a hydro-carbon gas which will 95 pass around the ends of the baffle wall 25 and upwardly through the pipe 18. This gas is ignited within the drum 19 and is there supplied with oxygen for complete combustion. The oxygen, as has previously 100 been stated, is uniformly distributed to the generated gas and smoke through the series of perforations 20 which extend circumferentially around the wall of the drum 19. The combustion of the gas within the drum 105 will rapidly raise the temperature of the drum and impart a large amount of heat to

the surrounding atmosphere, thereby heating the orchard without producing a smoke.

I claim:

1. In an orchard heater, an oil container consisting of a long flat box adapted to rest upon the ground and provided with a cover having an inlet opening at one end and an outlet opening at the other end, a baffle wall mounted crosswise of the box in front of the outlet opening and extending the height of the box and leaving openings upon each side, a cylindrical sleeve extending upwardly around the inlet opening, a cap fitting upon the sleeve; there being registering perforations through the cap and sleeve; a handle for rotating the cap, a pipe extending upwardly from the outlet opening, a drum mounted upon the upper end of the pipe; said drum being considerably larger than the pipe; and a baffle plate mounted horizontally in the drum above the end of the pipe; there being perforations all the way around the drum below and above the baffle plate.
2. In an orchard heater, an oil container

consisting of a long flat box adapted to rest upon the ground and provided with a cover having an inlet opening at one end and an outlet opening at the other end, a baffle wall mounted crosswise of the box in front of the outlet opening and extending the height of the box and leaving openings upon each side, a cylindrical sleeve extending upwardly around the inlet opening, a cap fitting upon the sleeve; there being registering perforations through the cap and sleeve; a handle for rotating the cap, a pipe extending upwardly from the outlet opening, a drum mounted upon the upper end of the pipe; said drum being considerably larger than the pipe; a baffle plate mounted horizontally in the drum above the end of the pipe; there being perforations all the way around the drum below and above the baffle plate; and a series of stay rods pivotally fixed to the sides of the drum and adapted to extend outwardly to the ground.

In testimony whereof I have signed my name to this specification.

JOSEPH PAXTON SIMPSON.
